UNITED STATES PATENT OFFICE.

THOMAS B. JONES, OF TURLOCK, CALIFORNIA.

PISTON RING.

1,423,943.

Specification of Letters Patent. Patented July 25, 1922.

Application filed May 25, 1921. Serial No. 472,333.

To all whom it may concern:

Be it known that I, THOMAS B. JONES, a citizen of the United States, residing at Turlock, in the county of Stanislaus and State 5 of California, have invented certain new and useful Improvements in Piston Rings, of which the following is a specification.

This invention relates to piston rings, and comprises a ring having its upper outer edge beveled, and its lower inner edge beveled or provided with tapering notches or preferably having its lower inner edge beveled and provided with tapering notches to permit passage of oil inwardly to the bottom 15 of the ring groove.

This application is a continuation, in part, of my copending application for piston rings, filed March 9, 1921, Serial No. 451,064.

Various constructions of piston rings have 20 been provided for the purpose of collecting surplus oil to prevent it from passing into the explosion chamber thereby fouling the spark plugs and causing carbon deposits on the cylinder heads and the top of the piston.

I have found that the use of oil collecting means is only practical in the lower ring groove or grooves of the piston to collect the oil and return it through openings in the pistons. To accomplish this object, I 25

provide a reservoir at the bottom of the lower ring groove and further provide means for drawing the oil inwardly to this reservoir on the downward stroke of the piston. The piston is further provided 30 with openings communicating with the reservoir in the bottom of the ring groove to permit the surplus oil to be returned to the crank case.

By providing a lower ring having its 40 upper outer edge beveled, the ring is prevented from carrying oil upwardly during the upward stroke of the piston and thus prevented from entering the explosion chamber. The lower outer edge of the ring

45 is provided with a sharp corner to scrape the surplus oil on the downward stroke of the piston and prevent it from passing by the ring. The surplus oil enters the reservoir formed by tapering the inner lower edge of the piston ring or providing notches 50 and is thence returned through the openings in the piston.

In the accompanying drawings, I have shown several embodiments of the invention. In this showing:

Figure 1 is a vertical sectional view of

a piston showing one form of the invention applied,

Figure 2 is a detail perspective view showing the ring detached,

Figure 3 is a detail view of the ring shown in Figure 2,

Figure 4 is a perspective view of another form of the invention, and,

Figure 5 is a similar view of a further 65 modification.

Referring to the drawings, the reference numeral 1 designates a piston of ordinary construction provided with a piston rod 2, connected thereto by means of a wrist pin 70 3. The piston is provided with upper grooves 4 arranged near the top and adapted to receive compression rings 5. As shown, these rings are rectangular in cross-section and are adapted to form a perfect 75 seal between the piston and the cylinder wall to prevent the explosive mixture from passing downwardly during the compression stroke of the engine.

The piston is further provided with a 80 lower ring groove 6, preferably disposed below the wrist pin and provided with a plurality of openings 7, communicating with the interior of the piston. A ring 8 is arranged in this groove, the ring being provided with an upper outer beveled edge 9, as shown. The lower outer edge of the ring is provided with a sharp corner 10. The lower inner edge is beveled as at 11, and may further be provided with spaced 90 notches 12.

In the form of the invention shown in Figure 4 of the drawings, the ring 13 is provided with the upper beveled edge shown in Figures 1 to 3, and in place of the lower 95 inner beveled edge, the ring is provided with a plurality of notches 14, slightly larger in size than the notches employed in the form shown in Figure 2 of the drawings.

In the form of the invention shown in Figure 5 of the drawings, a ring 15 is provided having an upper outer beveled edge (not shown) and a lower inner beveled edge 16. Each of the forms of rings may be provided with interlocking ends 17 of any desired construction.

In the form of the invention shown in Figures 1 to 3 of the drawings, the upper rings 5 carry sufficient oil upwardly during the upward stroke of the piston to lubricate 110 the cylinder and not present an excess of oil to be carbonized when the charge is fired.

By reason of the beveled edge 9, the lower ring does not carry oil upwardly on the upward stroke and there is, therefore, less oil present on that portion of the cylinder 5 wall traversed by the upper rings during the downward stroke than would be present if the beveled edge 9 were not employed on the lower ring. On the downward stroke of the piston, the sharp lower outer edge 10 scrapes the oil from the walls of the cylinder and feeds it into the bottom of the ring groove. During the downward stroke, the ring will be in its uppermost position 15 slightly spaced from the bottom of the ring groove and the oil will be drawn inwardly through the notches 12 to the reservoir formed at the inner edge of the bottom of the ring groove by the notches and the beveled edge. Thence the oil passes through 20 the opening 7 and returns downwardly through the interior of the piston to the crank case.

In the form of the invention shown in Figure 4 of the drawings, the operation is 25 essentially the same. The lower outer edge of the ring removes the surplus oil from the walls of the cylinder during the downward stroke and this excess oil passes through the notches 14 to the bottom of the groove 6, 30 and thence through openings 7.

In the form of the invention shown in Figure 5 of the drawings, which is intended

primarily for use with smaller engines, the oil enters the bottom of the ring groove and flows into the reservoir formed by the 35 beveled edge 16.

It is to be understood that the forms of my invention herewith shown and described are to be taken as preferred examples of the same, and that various changes in the shape, 40 size, and arrangement of parts may be resorted to without departing from the spirit of the invention or the scope of the subjoined claims.

Having thus described my invention, I 45 claim:

1. A piston ring comprising a body portion having parallel front and rear walls and parallel top and bottom forming relatively sharp corners at the inner upper 50 edge and lower outer edge, said ring being provided with an outer upper beveled edge and a lower inner beveled edge.

2. A piston ring provided with an outer upper beveled edge, a lower inner beveled 55 edge, and tapering notches arranged on the lower face of said ring.

In testimony whereof I affix my signature in presence of two witnesses.

THOMAS B. JONES.

Witnesses:

MARTIN A. KUDOLLO,
D. L. KOBRY.
